S. GOLDMAN.

HEEL.

APPLICATION FILED, MAY 5, 1919.

1,310,614.

Patented July 22, 1919.

Inventor:
Samuel Goldman
By *Samuel Goldman*

UNITED STATES PATENT OFFICE.

SAMUEL GOLDMAN, OF CHICAGO, ILLINOIS.

HEEL.

1,310,614.

Specification of Letters Patent. Patented July 22, 1919.

Application filed May 5, 1919. Serial No. 294,757.

To all whom it may concern:

Be it known that I, SAMUEL GOLDMAN, a citizen of the United States, residing at Chicago, in the county of Cook and State 5 of Illinois, have invented certain new and useful Improvements in Heels, of which the following is a specification.

Heretofore it has been the practice to provide metal heels with fastening prongs secured to the heel rigidly by casting or otherwise so that if one or more prongs becomes broken in applying the heel there is no way of replacing the broken prong and the heel cannot be used and therefore becomes a total 15 loss.

My invention has for its object to provide a metal heel with removable fastening prongs so that any of them can be replaced when required.

20 A further object of the invention is to provide a metal heel with removable fastening prongs so that the heels and the prongs may be more compactly packed together or packed separately for shipment.

25 In the accompanying drawings I have illustrated my invention in a metallic heel for a lady's shoe and referring thereto:

Figure 1 is a side view of the heel shown in its proper relation to a shoe which is indicated by broken lines.

30 Fig. 2 is a top plan view of the heel with the prongs in place.

Fig. 3 is a front view of the heel with the prongs in place.

35 Fig. 4 is an enlarged sectional view on line 4-4 of Fig. 2.

Fig. 5 is a perspective view of a prong.

Referring to the drawings 6 is a metallic heel which can be made in any suitable 40 shape and size. This heel is preferably made of aluminum and cast hollow in its upper portion at least. A plurality of ledges 7 are cast integral within and around the upper edge thereof and slightly below said edge. These ledges are provided with threaded sockets 8 to receive the threaded heads 9 of the prongs 10. The head of each prong is provided with at least two parallel squared sides 11 to accommodate a tool for

inserting or removing the prong from the heel.

In applying a heel it is customary to press the prongs against the shoe to mark the position thereof and then to make holes in the shoe at the prong marks with an awl or other tool. Then the prongs are inserted in these holes the heel driven to place after which the prongs are bent over inside the shoe and covered with an inner sole. If a prong is broken during the application of the heel, the heel may be removed from the shoe, a new prong substituted for every broken prong and the heel applied as before explained. My invention prevents the waste and loss of heels due to breakage of the prongs in applying them to shoes and it also enables the heels to be packed separately for shipment or the prongs may be loosely arranged in the hollow of the heel but not connected therewith.

The invention provides a great saving to cobblers who have heretofore suffered the loss of the entire heel whenever a prong was broken in applying a heel to a shoe. It is necessary that all the prongs provided for the purpose should be properly engaged with the shoe to hold the heel in place and if any prong is broken there has been no means of replacing it. My invention provides a simple means for replacing any prongs broken during the application of the heel, or during the removal of the heel for any purpose.

The ledges are located on an incline or otherwise sufficiently below the top edge of the heel so that the squared portions 11 of the heads of the prongs will lie below the plane of the edge of the heel and thus not interfere with the application of a heel to the shoe.

I claim:

1. The combination of a metallic heel having a plurality of ledges arranged within its upper edge and threaded sockets in said ledges, and prongs having threaded heads removably secured in said sockets.

2. A metallic heel having a plurality of ledges arranged within its upper edge and

sockets in said ledges below the plane of said edge of the heel, and prongs screw threaded in said sockets.

3. A metallic heel having a hollow upper portion, a plurality of ledges located within the upper edge of the heel and below the plane of said edge and provided with sock-

ets, and prongs having heads screw threaded in said sockets and squared portions at the top of said heads.

SAMUEL GOLDMAN.

Witness:

B. C. GOLDMAN.
